Primary Examiner — Karen E Kearney*Assistant Examiner* — Michelle K. Lu(57) **CLAIM**

The ornamental design for a LED projector light, as shown and described.

DESCRIPTION

FIG. 1 is a top perspective view showing of a LED projector light;

FIG. 2 is a bottom perspective view showing of the LED projector light;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the LED projector light that form no part of the claimed design.
